UNITED STATES PATENT OFFICE.

JOSEPH L. JOYCE, OF NEW HAVEN, CONNECTICUT.

BOX-TOE FOR BOOTS AND SHOES.

SPECIFICATION forming part of Letters Patent No. 288,944, dated November 20, 1883.

Application filed October 8, 1883. (No model.)

To all whom it may concern:

Be it known that I, JOSEPH L. JOYCE, of New Haven, in the county of New Haven and State of Connecticut, have invented new Improvements in Box-Toes for Boots and Shoes; and I do hereby declare the following, when taken in connection with accompanying drawings and the letters of reference marked thereon, to be a full, clear, and exact description of the same, and which said drawings constitute part of this specification, and represent, in—

Figure 1, a side view of the toe portion of a boot or shoe, showing my improvement; Fig. 2, a vertical central section of the same; Fig. 3, a perspective view of the toe-piece made as an independent article; Figs. 4, 5, and 6, modifications.

This invention relates to an improvement in that class of boots and shoes in which the toe is protected by an extra thickness, commonly called "box-toes."

In the usual construction of this class of shoes the upper is made of the full extent, and so as to surround and cover the toe portion. Then over the toe portion an extra thickness is applied, stitched across the toe, and turned under with the upper. The outer thickness overlies the upper and increases the extent of the toe portion of the shoe beyond the surface of the upper, giving to the toe portion a clumsy appearance. The edge, as well as the whole toe portion, is exposed to severe wear and soon breaks. Again, boxing adds considerably to the expense of the shoe, for the reason that the upper, which is necessarily of fine quality of leather, must extend entirely over the toe beneath the cap or boxing.

The object of my invention is to produce the toe portion of the shoe from a single thickness of leather, whereby a saving in the upper will be made, the toe stronger than in the usual construction, and avoid the difficulties generally which are experienced with this class of toes; and the invention consists in a toe-piece having its rear edge recessed to receive the edge of the upper, which is cut off at the toe-line, the upper and toe-piece stitched together, and so as to form substantially a continuous smooth surface from the upper down over the toe-piece, as more fully hereinafter described.

A represents the toe-piece, which is best

made from leather of two or three times the thickness of the upper. At its rear edge it is recessed to form a shoulder, *a*, in depth corresponding substantially to the thickness of the upper *B*, and upon the under side the toe-piece is chamfered, as at *b*; or the chamfering may be upon the upper side, and the under side turned upward to bring the upper surface into a plane corresponding to the under side of the upper, as seen in Fig. 2. This toe-piece may be struck up in dies into the required shape, as seen in Fig. 2, leaving a portion, *d*, around its lower edge for attachment to the sole; or it may be made flat, as seen in Fig. 4, and the upper cut to fit the shoulder, and stitched thereto, as indicated in Fig. 4, and so as to leave the surface of the upper and the surface of the toe-piece substantially in a continuous plane or flush surface, as seen in Figs. 1 and 2.

In cutting the boot or shoe the upper is cut short of the full extent of the foot portion, corresponding to the toe-piece from the shoulder *a* forward; hence a great saving is made in cutting the uppers, not only in saving of material in each individual shoe, but because the upper may be cut from a less extent of material, and thereby avoid defects in the leather, which would destroy a large portion were it not for such short cutting. The toe-pieces may be made from scraps of thicker leather, such as produced by various manufactures employing a thicker grade of leather.

In lasting the shoe a considerable saving is made, for the reason that in the usual construction, where there is an overlying cap, the upper must first be smoothly lasted around the toe, and then the cap or boxing piece drawn smoothly over it. In the case of a struck-up toe-piece, lasting around the toe is almost entirely saved, as the toe-piece at once fits the last; or if made, as in Fig. 4, to be lasted, then there is only a single thickness to work over the toe, instead of two thicknesses, as in the usual construction.

Another advantage of this construction is that in making the toe-piece as I have described it is much stronger and firmer than can be made in the use of the two thicknesses, and is not liable to injury by wear, first, because the edge is not exposed, and, second, because of its thickness it is more durable.

In some cases it may be desirable to cover the box portion A with a different leather, as "patent-leather." In that case the covering-leather D is placed upon the boxing and struck 5 or worked down with the thicker or boxing portion to form the shoulder a, to receive the upper, as seen in Fig. 5.

The box-toe portion A, struck into the required shape, may be made as an article of manufacture and sold to shoe-manufacturers 10 to be applied.

In case of that class of shoes in which the uppers are made from thick leather, the recess and shoulder may be made on the upper, 15 and the toe-piece lapped onto the upper against the shoulder, so as to bring the surface of the two flush, as seen in Fig. 6.

I am aware that box-toes have been made from thick leather, and the upper cut off for 20 attachment to such thick toe, and therefore do

not claim, broadly, a thick leather or material box-toe for boots and shoes.

I claim—

1. The herein-described improvement in box-toed shoes, consisting in the toe-piece and upper cut in separate parts, the one part constructed with a recess upon the outside to form a shoulder, a, the other lapped onto said recessed portion and against the shoulder to bring the surface of the toe-piece and upper 30 flush upon the outside, substantially as described.

2. A box-toe for boots and shoes, struck into shape from leather, and constructed with a recess and shoulder, a, across its upper edge, 35 substantially as described.

JOS. L. JOYCE.
